[57] CLAIM

The ornamental design for a religious ornament for jewelry or the like, substantially as shown.

DESCRIPTION

FIG. 1 is a front elevational view of a religious ornament for jewelry or the like, showing my new design;
FIG. 2 is a top view of same;
FIG. 3 is an end elevational view of same, and taken from the right hand side of FIG. 1;
FIG. 4 is a bottom plan view thereof;
FIG. 5 is an end elevational view thereof, taken from the left hand side of FIG. 1; and FIG. 6 is a rear elevational view thereof, taken from the rear of FIG. 1.
